HAY PRESS

Paul P. Miller, Ottumwa, Iowa, assignor to Dain
Manufacturing Company of Iowa, Ottumwa,
Iowa, a corporation of Iowa

Application April 8, 1938, Serial No. 200,822

5 Claims. (Cl. 100—24)

The present invention relates to hay presses and has particularly to do with block dropping means for dropping division blocks into the baling chamber. It is the principal object of the present invention to provide means for dropping the division blocks automatically as the block holder arrives at dropping position.

More specifically, it is the object of the present invention to provide improved and simple latch means for holding the block in place in the holder, and trip means for disabling the latch to drop the block when the holder has reached a predetermined dropping position.

In the accompanying drawing illustrating a preferred embodiment of my invention:

Figure 1 is a sectional side view of a portion of a hay press showing the block holder in position intermediate its loading and dropping positions;

Figure 2 is a view similar to Figure 1 showing the block holder in dropping position with the latch disabled; and

Figure 3 is a detail sectional view taken along the line 3—3 of Figure 2.

Referring now to the drawing, the baling press comprises the usual frame having fore and aft extending angle iron bars 10 to which sides 11 and a bottom (not shown) are secured, enclosing a baling chamber which is indicated in its entirety by the reference numeral 12. The material to be baled is fed into the baling chamber 12 and is therein compressed by the usual plunger; the completed bales being pushed rearwardly along a compression chamber 10' defined by the angle iron members 10. Division blocks 13 having grooves 14 through which the binding wire is fed, are placed between the bales, and heretofore this operation has been performed by hand, the blocks being placed in position to the rear of each bale after it has been pushed out of the baling chamber 12 and along the compression chamber 10'. The block 13 must be dropped into place in the baling chamber 12 before or simultaneous with the fresh charge of material to be compressed, and must be fully seated in proper position before the beginning of the next compression stroke of the plunger. Should the block 13 fail to seat properly and the plunger ram the following charge of material thereagainst, the result quite frequently is breakage of the block or damage to the machine. Consequently it has been necessary to run the machine at a slower speed to permit more accurate placement and timing of the division blocks, reducing the capacity of the press.

With the above in view I have provided means for quickly and accurately dropping the blocks into place, said means comprising a holder, indicated generally at 15, which is pivotally connected to the press frame for swinging about a transverse axis between a loading position and a dropping position. The block holder 15 includes a frame 16 having four sides disposed in the form of a rectangle and adapted to receive one of the blocks 13, as shown in Figure 1. The upper edge of the frame 16, as viewed in Figure 2, is flared outwardly as at 17 to facilitate placing the block into the frame. The block holder 15 is swingably supported on the hay press frame by means of legs 20 which are fixed to the back side of frame 16 and which are pivotally connected at 21 to lugs 22 fixed to the top angle iron bars 10. A short leg 23 is welded or otherwise suitably secured to the leg 20 adjacent the pivot connection 21 providing a stop which is adapted to bear upon the top of angle iron bar 10 when the block holder is swung back into loading position, locating the frame 16 in a convenient position for placing blocks 13 therein. A U-shaped strap 24 is fixed to the legs 20 intermediate the ends thereof to provide a handle for swinging the block holder from loading to dropping positions.

The block 13 is held in the frame 16 by means of a spring latch 25 comprising a strap 26 which is pivotally connected midway of its length by a pin 30 to a U-shaped bracket 31 fixed to the frame 16. One end of the strap 26 is bent into the shape of a transversely disposed wedge 32 which is adapted to extend through a recess 33 cut into the lower edge of the side of the frame and projects above the surface of the inside thereof to engage a shoulder 34 formed in the lower edge of the block 13. The other end of the strap 26 is provided with a rectangular slot 35 cut back from the end of the strap to receive a post 36 which is fixed perpendicular to the frame 16. A compression spring 40 encircling the post 36 between the strap 26 and frame 16 exerts pressure against the strap to hold the wedged end 32 yieldingly against the block shoulder 34. A retaining washer 41 and cotter pin 42 hold the slotted end of the strap 26 from going beyond the end of the post 36.

The spring latch 25 is disabled by means of a trip bar 43 comprising an angle bracket which is bolted or otherwise suitably fixed to the strap 26 and which extends beyond the plane defined by the lower edges of the legs 20. As the block holder 15 swings down into dropping position 55 and the legs 20 descend upon the upper edge of

the baling chamber side 11, the trip bar 43 strikes the edge of the side of the chamber a moment before the legs 20 strike, depressing the trip bar 43 and strap 26 against the pressure exerted by the spring 40. This causes the wedged end 32 to be withdrawn into the recess 33, permitting the block 13 to drop down into the baling chamber under the force of its momentum and guided by the broad sides of the frame 16.

The advantage of this type of construction is that the block 13 can be loaded into the holder frame 16 in a convenient loading position, and the holder then swung quickly into dropping position by means of the handle 24 to drop the block into the chamber at just the right moment. Inasmuch as the block is dropped each time from the same position with the frame 16 acting as a guide, placement of the blocks is more accurate and damage due to improper seating is practically eliminated. Another important feature is the fact that the operator is not required to reach down into the baling chamber while placing the blocks and therefore is not exposed to the danger of getting a hand caught between the plunger and baling chamber.

What I claim as my invention is:

1. In a hay press having a body including a baling chamber, means for dropping division blocks into said baling chamber comprising a block holder pivotally connected to said body for swinging movement between a loading position and a dropping position, releasable latch means carried on said holder for holding the block in place, and trip means engageable with said hay press body as said holder swings into dropping position for moving said latch means to inoperative position.

2. In a hay press having a body including a baling chamber, means for dropping division blocks into said baling chamber comprising a block holder connected to said body for swinging movement between a loading position and a dropping position, a latch pivotally connected to said block holder and adapted to engage and restrain the block held therein, spring means for yieldingly holding said latch against the block, and trip means comprising an arm fixed to said latch and adapted to contact said body when said holder swings into dropping position to pivot said latch

against the pressure of said spring means out of engagement with the block and permit the latter to drop into said baling chamber.

3. In a hay press having a baling chamber, a block dropper comprising a block holder, a pair of supporting legs fixed thereto, means pivotally connecting said legs with said hay press whereby said holder is swingable from a loading position to a dropping position over said chamber, said legs being adapted to contact the side of said chamber to arrest the movement of said holder when the latter has reached said dropping position, a releasable latch for retaining a block in said holder, and trip means engageable with the side of said chamber as the holder approaches said dropping position for moving said latch to inoperative position whereby said block is allowed to drop into the baling chamber with unchecked momentum.

4. In a hay press having a baler frame and a block holder connected therewith for movement into and out of block dropping position, a latch carried by said block holder and adapted to maintain the block in position within the holder, said latch being movable between block holding and inoperative positions, and means responsive to relative movement between said holder and said baler frame for moving said latch to inoperative position as the holder approaches dropping position.

5. In a hay press having a body including a baling chamber, a device for dropping division blocks into said baling chamber comprising a block holder supported on said body for vertical swinging between a loading position and a dropping position over said chamber, a releasable latch pivotally connected intermediate its ends to said block holder, said latch having one end shaped to engage said block for restraining the same against dropping, a spring acting against the other end of the latch to hold said one end in engagement with the block, and a trip arm fixed to said latch adjacent said other end, said trip arm being engageable with said body as the block holder approaches said dropping position for moving the latch out of engagement with the block against the tension of said spring to allow the block to drop into the baling chamber.

PAUL P. MILLER.
